UNITED STATES PATENT OFFICE.

HEINRICH SÜSSMANN, OF BERLIN, GERMANY, ASSIGNOR TO DEUTSCHE GASGLÜHLICHT-AKTIENGESELLSCHAFT, OF BERLIN, GERMANY, A FIRM.

GAS-BURNER.

No. 823,308.

Specification of Letters Patent.

Patented June 12, 1906.

Application filed February 26, 1904. Serial No. 195,360.

To all whom it may concern:

Be it known that I, HEINRICH SÜSSMANN, manager, a subject of the German Emperor, residing at 144 Alte Jacobstrasse, Berlin, in 5 the Empire of Germany, have invented certain new and useful Improvements in Gas-Burners, of which the following is a specification.

Nozzles with adjustable outlet-apertures 10 for Bunsen burners are already known, which consist of a cap open at its lower part and cut into a number of parts, these parts being adapted to be compressed to a greater or less extent by means of a nut screwed over them.

15 The regulating device, which forms the subject of this application, differs from these known nozzles, owing to the fact that the adjustment of the outlet-slit in the divided cap is produced by its adjustability relatively to 20 a restriction in the nozzle-casing which receives it. This adjustment may be effected by means of a set-screw, for example.

The restriction in the nozzle-casing may consist of a cone of greater or less length, 25 against which the front end of the cap is displaced, thereby causing the divided portions of the cap to yield relatively one to the other. By reducing the outlet-aperture when the gas-pressure increases and enlarging it when 30 the pressure decreases the quantity of gas issuing from the nozzle may be maintained constant. The velocity with which the gas enters the mixing-chamber thus varies with the magnitude of the gas-pressure.

35 If it is desired to maintain the discharge velocity constant as well as the quantity discharged, this may be effected in accordance with this invention by providing that the adjustable cap shall not itself form the outlet-aperture directly, a special mouthpiece, with 40 invariable outlet-apertures, being arranged above the said adjustable cap. In this manner an increase of the discharge velocity as a result of the restriction of the discharge-aperture of the adjustable cap is obviated. A 45 collecting or pressure chamber may thus be formed between the outlet-mouthpiece and the adjustable cap, which chamber facilitates the uniform discharge of the gas. In this 50 case, therefore, the adjustment to suit the gas-pressure for the time being merely produces a regulation of the quantity of the gas discharged, while the discharge velocity at the nozzle-mouthpiece is not altered, or not 55 to any appreciable extent. This novel nozzle

is illustrated in two constructional forms in the accompanying drawings—that is to say in Figures 1, 2, and 3—with a single cap with adjustable slit-apertures, of which—

Fig. 1 is an elevation of burner and mantle. Fig. 2 is a sectional elevation, and Fig. 3 is a plan view, with the mixing-tube omitted. Figs. 4, 5, and 6 represent a constructional form with a cap presenting adjustable slit-apertures and with special mouthpiece with 65 invariable discharge-apertures. Fig. 4 is a sectional elevation. Fig. 5 is a plan view with the mixing-tube omitted, and Fig. 6 is a section on the line 1 1 of Fig. 4.

The nozzle-casing *a* is similar to an ordinary five-hole nozzle. It may be made in one piece, Fig. 2, or in two pieces, Fig. 4. A tightly-working lateral screw *c* is introduced through its wall, this screw being formed with a finely-tapering conical point. By means 75 of this point the cap *b*, which is divided by two continuous slits into four divisions, may be raised or lowered. As the cap *b* bears at its other end against a conical restriction *e* of the nozzle-casing *a*, by tightening up the 80 screw *c* the yielding walls of the cap are compressed, so that the slit-apertures become narrower. The conically-tapering screw-point acts in the manner of a wedge in effecting this. When the screw is slackened, the 85 cap moves back against the inclined faces *e*, owing to the pressure of the parts, which tend to separate. By making the taper on the screw-point very gradual the regulation of the 90 flow of gas may be very nicely effected. In order to prevent the cap or socket *b* from falling down if the screw *c* should be withdrawn 95 too far, a second small screw or pin *d* may be provided—say in the hollow of the nozzle-casing beneath the cap.

Above the adjustable slit-apertures (see Figs. 4 to 6) the chamber *h* may be provided, this chamber being closed externally by the mouthpiece-plate *i*, which contains the invariable outlet-apertures. This chamber *h* 100 serves as a collecting and pressure-equalizing reservoir and assists in producing the uniform discharge of the gas from the invariable apertures in the plate *i*, while by means of the set-screw *c* the slit-apertures in the cap *b* are 105 adjusted in agreement with the prevailing gas-pressure.

All the parts may vary from those illustrated in the drawings in their construction. Instead of two intersecting slits in the cap 110

either one such slit or three or more may be provided. In place of the set-screw with conically-tapering point any other suitable device may be employed for displacing the cap. It is immaterial whether the Bunsen burner is upright, downwardly directed, or inclined. The main feature is that in all cases it is possible to maintain constant the quantity of gas discharged and also, if desired, the discharge velocity with varying gas-pressure by adjusting the slit-apertures in such a manner that the proper mixing proportion between gas and air may be maintained in the Bunsen burner.

15 What I claim, and desire to secure by Letters Patent of the United States, is—

1. A gas-burner, comprising a nozzle-casing having an internal beveled surface inclining downwardly and outwardly, a slitted 20 spring-cap mounted to slide in the casing and having its upper end tapering inwardly and upwardly, and a screw having a pointed end and mounted in the casing with its pointed end projecting into said casing below the 25 lower end of the cap, whereby the slits of the cap are contracted when the cap is moved upwardly.

2. A gas-burner comprising a nozzle-casing having an internal beveled surface inclining downwardly and outwardly, a slitted 30 spring-compressible cap adapted to slide lengthwise of the casing and having its upper end tapering inwardly and upwardly, a screw projecting with its pointed end into said casing and adapted to adjust the cap lengthwise 35 and support it in all positions, and means projecting into the casing for preventing said cap from falling out.

3. A gas-burner comprising a nozzle-casing having a detachable head-piece provided with an internal beveled surface, a slitted spring-compressible cap adapted to slide lengthwise of said head-piece and having a beveled upper outer end, an adjusting-screw projecting into the casing below the head-piece and the cap and adapted to support the cap in all positions, and means also projecting into the casing below the cap, for preventing said cap from falling out. 40 45

4. A gas-burner, comprising a nozzle-casing having an internal beveled surface and above the beveled surface, a chamber having an apertured top plate, a slitted spring-cap in the casing and having a beveled upper end, and a screw having a pointed end and mounted 50 in the casing with its pointed end projecting into the said casing below the lower end of the said cap. 55

5. A gas-burner, comprising a nozzle-casing having an internal beveled surface inclining downwardly and outwardly and above said surface a chamber having an apertured top plate, a slitted spring-cap in the casing and having its upper end beveled inwardly and upwardly, and a screw having a pointed 60 end and mounted in the casing with its pointed end projecting into the casing below the lower end of the cap. 65

In testimony whereof I have hereunto set my hand, in presence of two subscribing witnesses, this 12th day of February, 1904. 70

HEINRICH SÜSSMANN.
